UNITED STATES PATENT OFFICE.

ALICE ELAINE WARFMAN, OF NEW YORK, N. Y.

DESIGN FOR A CAPE.

Application filed October 9, 1925. Serial No. 15,075. Term of patent 3½ years.

To all whom it may concern:

Be it known that I, ALICE E. WARFMAN, a citizen of the United States, and a resident of the city of New York, borough of the Bronx, in the county of Bronx and State of New York, have invented a new, original, and ornamental Design for Capes, of which the following is a specification, reference being had to the accompanying drawings, forming part thereof.

I claim:

The ornamental design for a cape, as shown.

ALICE ELAINE WARFMAN.
